UNITED STATES PATENT OFFICE.

WALTER M. KEIGHLER, OF PHILADELPHIA, PENNSYLVANIA.

GAS-HEATED STEAM-RADIATOR.

1,237,343.

Specification of Letters Patent. Patented Aug. 21, 1917.

Application filed December 14, 1916. Serial No. 137,004.

To all whom it may concern:

Be it known that I, WALTER M. KEIGHLER, a citizen of the United States, residing at Philadelphia, in the county of Philadelphia and State of Pennsylvania, have invented 5 new and useful Improvements in Gas-Heated Steam-Radiators, of which the following is a specification.

My invention relates to new and useful 10 improvements in gas heated steam radiators, and has for its object to provide an exceedingly simple and effective device of this character, which may be placed in a building without the necessity of running the 15 ordinary pipes through the building from a central heating plant, thereby providing a device which will be relatively inexpensive in the cost of installation.

A further object of the invention is to 20 provide a device of this character in which the heater is combined with the radiator, so that the device may be readily installed in any part of a building provided with gas fixtures.

25 Another object of the invention is to provide a gas heated radiator which will be relatively inexpensive in the cost of manufacture, although strong and durable, which will need little or no attention during use, 30 and which will produce a maximum amount of heat with the consumption of a minimum amount of fuel.

With these ends in view, this invention 35 consists in the details of construction and combination of elements hereinafter set forth and then specifically designated by the claims.

In order that those skilled in the art to 40 which this invention appertains, may understand how to make and use the same, I will describe its construction in detail, referring by numerals to the accompanying drawing forming a part of this application, in which—

45 Figure 1 is a front elevation of a gas heated radiator constructed in accordance with my invention, portions thereof being shown in section, and parts being broken away to clearly illustrate the construction.

50 Fig. 2 is a cross section of the heater.

In carrying out my invention as here embodied 2 represents a radiator of any desirable size and construction adapted to stand upon the floor or hinge from the wall by 55 means of brackets, and this radiator is provided with the ordinary steam valve 3. At

one end of the radiator, and at the top thereof is connected a pipe 4 leading to the interior of the radiator, and to the outer end of this pipe is connected the T coupling 5. 60 To the lower opening of this T coupling is connected one end of a pipe 6, the opposite end being connected with one of the openings of the reduced T coupling 7. Intermediate the ends of this pipe 6 is arranged a 65 try-cock 8 which acts as a water gage, and which may be opened when the radiator is being filled with water to prevent the contents of the radiator reaching a greater height than the position of this try-cock 8. 70

To one of the other outlets of the coupling 7 is connected a horizontal pipe 9 running the entire length of the radiator some suitable distance below the same, and to this pipe is connected an elbow coupling 10 having one end of a pipe 11 connected thereto, and to the opposite end of this pipe is connected another elbow 12 to which is connected a pipe 13 running to the opposite end of the radiator at the bottom thereof, and 80 communicating with the interior of said radiator.

In the upper outlet opening of the T coupling 5 is threaded a filling cup or funnel 14 having external and internal threads in 85 the stem portion thereof. This filling cup permits the water to be readily placed in the radiator without the likelihood of spilling the same, and when the radiator is filled to the proper capacity, a suitable closure or 90 closing plug 15 is threaded into the threaded portion of the filling cup, and this closure is provided with a suitable stem or handle 16, whereby the same may be readily and 95 quickly removed or replaced, and this stem or handle projects above the upper edge of the filling cup when the closure is in its closed position.

In the reduced end or outlet of the T coupling 7 is mounted a pet-cock 17, 100 whereby the contents of the radiator may be drawn therefrom. The fire box 18 is mounted upon and supported by the pipe 9, said pipe projecting through both ends of said fire box and the walls of this fire box 105 are imperforate. This fire box has one open side which is normally covered by a lid 19 hinged to one of the walls of the fire box by means of hinges 20, and this lid is provided with perforations 21 for the admission of air to the fire box, thus providing 110 for the proper combustion of the gas within

the fire box. If found desirable this lid may be held in a closed position by a suitable catch 22.

That portion of the pipe 9 situated within 5 the fire box is preferably covered with a jacket or sleeve 23 of copper or other suitable metal having high fire resisting properties, and this sleeve or jacket also acts as a heat retainer and transmitter, so that 10 the water in the pipe 9 will be readily raised in temperature until steam is finally produced therefrom, which will circulate through the pipes 9, 6 and 4, then through the radiator, whereby it will gradually cool 15 and condense and return to the lower portion of the radiator in the form of water, from which point it will circulate through the pipes 13 and 11 into the pipe 9 to be again heated and turned into steam.

20 In the fire box 18 below the pipe 9 is arranged a gas burner 24 in the form of a Bunsen burner, so that a very hot, blue flame will be produced, and this burner is connected by a pipe 25 or its equivalent, 25 such as a hose, with the gas supply pipe 26 in the form of an outlet pipe or gas fixture.

In actual practice it is only necessary to replenish the radiator with water in small amounts every one or two weeks, and it has 30 been found that the consumption of gas is very small; so that it will be understood that my radiator may be installed in houses, which at the present time do not use steam because of the expense of installing such

devices, caused by the necessity of having 35 to pipe the building.

Of course I do not wish to be limited to the exact details of construction as herein shown, as these may be varied within the limits of the appended claims without departing from the spirit of my invention.

Having thus fully described my invention, what I claim as new and useful, is—

1. The combination with a circulation pipe adapted to be connected at its ends to 45 a radiator; of a heater comprising a casing having a conducting sleeve extending across the same and supported thereby and closely inclosing a section of said pipe, a burner in the casing, under the sleeve, and 50 means for supplying air to the burner within the casing and for allowing the products of combustion to escape from the casing.

2. The combination with a circulation 55 pipe adapted to be connected at its ends to a radiator; of a heater comprising a casing having a straight metal sleeve extending through opposite end walls of the casing and between the same; a section of the pipe 60 extending through said sleeve, a burner in the casing, under the sleeve, and means for supplying air to the burner within the casing and for allowing the products of combustion to escape from the casing.

In testimony whereof, I have hereunto affixed my signature.

WALTER M. KEIGHLER.
